UNITED STATES PATENT OFFICE.

GEORGE A. JOHNSON, OF CHICAGO, ILLINOIS, ASSIGNOR TO WILLIAM H. MINER, OF CHAZY, NEW YORK.

ROCKER SIDE BEARING.

1,300,405.

Specification of Letters Patent. Patented Apr. 15, 1919.

Application filed July 25, 1918. Serial No. 246,624.

To all whom it may concern:

Be it known that I, GEORGE A. JOHNSON, a citizen of the United States, residing at Chicago, in the county of Cook and State of Illinois, have invented a certain new and useful Improvement in Rocker Side Bearings, of which the following is a full, clear, concise, and exact description, reference being had to the accompanying drawings 10 forming a part of this specification.

This invention relates to improvements in rocker side bearings.

The object of the invention is to provide a simple and relatively inexpensive rocker 15 side bearing for railway cars wherein the rocker is suspended under the influence of gravity and the parts so designed that the rocker will be automatically self-centered after each actuation.

20 In the drawings forming a part of this specification, Figure 1 is a vertical, sectional view, taken transversely of the body and truck bolsters of a railway car and showing my improvements in connection therewith. 25 And Fig. 2 is a sectional view taken substantially on the line 2—2 of Fig. 1. In said drawing, 10 denotes the upper bearing portion of a truck bolster of a railway car and 11 the corresponding under portion of 30 a car body bolster. The improved side bearing is shown as comprising, broadly, a retaining casting A, an anti-friction rocker B, and a supporting bolt or pin C.

The retaining member A is preferably in 35 the form of a casting and is provided with an upper bearing wall 12, depending side walls 13—13, depending end walls 14—14, perforated ears 15—15 by which the member A is riveted or otherwise secured to the 40 body bolster, and suitable bracing flanges 16—16 for the end walls 14. From the preceding description, considered in connection with the drawing, it will be seen that the retaining member A is hollowed out 45 on its under side so as to form a box-like structure to accommodate the rocker B.

The antifriction rocker B is in the form of a casting substantially reniform in cross section. The rocker B is provided with an 50 upper bearing surface 17 which engages with the under face or bearing surface of the portion 12 of the retaining member and in addition, the rocker is provided with a lower curved bearing surface 18 adapted to 55 engage the upper surface of the truck bol-

sters. The bearing surfaces 17 and 18 are made concentric so as to maintain a constant distance between the two bolsters when the rocker is in service, as will be understood. The rocker is freely supported by 60 means of the bolt C which extends through a suitable perforation in the rocker B and is free to move in elongated slots 19—19 in the side walls of the retaining member A.

It will be noted that the retaining member A is provided on its interior with a plurality of knobs or teeth 20—20 which coöperate with corresponding recesses 21—21 in the upper bearing face of the rocker B. In this manner, the rocker B is always positively returned to its central normal position after each actuation since the teeth 20 and recesses 21 will always maintain the same relation between the rocker B and retaining member A. In this manner, I overcome a defect heretofore encountered in 70 some types of gravity side bearings.

The dotted lines in Fig. 1 show one extreme position of the rocker and it will be noted that the lower portions of the end 80 walls 14 are rounded or flared outwardly, as indicated at 22, so as to fit the indented portions 23 on the sides of the rocker and thus limit the movements of the rocker. This construction results in an upwardly 85 directed pressure on the end walls of the retaining member A instead of a straight horizontal outward thrust and thus relieves the strain on the end walls and prolongs 90 the life thereof.

It will be obvious to those skilled in the art that various changes and modifications may be made in the details of construction without departing from the spirit of the invention and I contemplate all changes and 95 modifications that come within the scope of the claims appended hereto.

I claim:

1. In a side bearing adapted for railway cars and the like, the combination with a 100 retaining casting provided on its under side with a bearing surface and depending spaced side walls, of an anti-friction rocker having an upper bearing surface coöperable with that of said casting and provided also 105 with a lower bearing surface adapted to engage an opposed member, and means for suspending said rocker freely from said casting, said means comprising a rod extending transversely through said rocker, the 110

ends of said rod being movable in slots provided in said depending side walls of the casting, said slots being formed in accordance with the path traveled by the ends of said rod as the latter moves with the rocker;

2. In a side bearing for railway cars and the like, the combination with a hollow box-like casting adapted to be secured to the body bolster of a car, said casting having a bearing surface and provided with a plurality of depending projections, of an anti-friction rocker, means for suspending said

rocker freely from said casting, said rocker having recesses in its upper face for co-operation with said projections, and means 15 for limiting the movement of said rocker.

In witness that I claim the foregoing I have hereunto subscribed my name this 18th day of July, 1918.

GEORGE A. JOHNSON.
